UNITED STATES PATENT OFFICE.

RODNEY S. PULLEN, OF ATLANTIC CITY, NEW JERSEY.

CIGARETTE-MAKING DEVICE.

1,411,933.

Specification of Letters Patent.

Patented Apr. 4, 1922.

Application filed March 31, 1920. Serial No. 370,170.

To all whom it may concern:

Be it known that I, RODNEY S. PULLEN, a citizen of the United States, and resident of Ventnor, Atlantic City, county of Atlantic, 5 and State of New Jersey, have invented an Improvement in Cigarette-Making Devices, of which the following is a specification.

The object of my invention is to provide a suitable device to be carried by a smoker, 10 for conveniently making cigarettes in which the tobacco may be compressed to the degree desired.

My object is further to so construct the device that it may be combined with the container or bag for the tobacco and adapted to 15 the making of cigarettes in such manner that the tobacco is not exposed and is, therefore, proof against loss from wind currents when used outdoors.

20 A further object is to provide means by which perfect cigarettes, both as to shape and packed contents, may be made, even by a novice or unskilled maker of cigarettes.

My invention also consists of improvements hereinafter described whereby the 25 above objects and results are attained, said improvements comprising certain organization and combination of parts which are fully described hereinafter and more particularly defined in the claims.

Referring to the drawings: Fig. 1 is an elevation of my improved cigarette making device removed from the bag or container; Fig. 2 is an end view of the same; Fig. 3 35 is an elevation of a bag of tobacco having my improved device applied thereto and as employed in the act of making a cigarette; Fig. 4 is a perspective view of a modified form of the device with the tube in dotted 40 lines; Figs. 5 and 6 are respectively an elevation and end view of another modification of my invention; Fig. 7 is a sectional view showing a further modification of my invention; and Fig. 8 is a perspective view of a 45 still further modification of my invention.

A wire frame of general rectangular shape is formed of side parts 2 and 4 connected at the bottom through a circular coil 3 and at the top by welding or soldering the end of 50 the wire part 4 to the upper extension of the wire part 2, as shown in Fig. 1; and the upper part of wire 2 is bent downwardly, as at 6 to constitute a plunger, with its lower end free and in alinement with the opening in 55 the circular coil 3 which is provided on the junction of the parts 2 and 4 employed as

extensions from the plunger 6. A tube 7 is loosely supported and guided in the circular coil part 3, so as to be freely slideable therein, so that the wire end 6 may enter the tube and act as a plunger thereto. The upper end of the tube 7 is flared as at 8, to prevent it passing out of the coil part 3 and also to better guide the tobacco into the tube. In practice, 60 the tube 7 is held near the bottom by the fingers and the frame and its plunger reciprocated vertically, so that the coil 3 is guided upon the outer wall of the tube, while at the same time the plunger 6 enters the interior of the tube or barrel 7 to pack the tobacco. 65

In use, the device shown in Figs. 1 and 2 is inserted into the bag 10 of tobacco, with the tube 7 projecting; the mouth 11 of the bag is then closed upon the tube by the drawing strings 12, as shown in Fig. 3. 70

In using the device for making a cigarette, it is manipulated in the following manner: The tube 7 is drawn out of the bag or container as far as possible and a cigarette paper sheet is then wrapped about the tube and the 75 edge of the paper wetted with the tongue to insure its adherence. The lower end of the paper tube 13 is turned inward over the bottom of the tube as at 14 (Fig. 3). The paper tube 13 is then drawn down upon the tube 7 80 for about half its length (Fig. 3) and held to the tube 7 by the thumb and finger; and the tobacco falls through the tube 7 into the paper tube 13, and may be packed therein by manipulating the wire plunger 6 within the 85 tube 7. The result of this is that the tobacco is caused to find its way into the tube and positively moved through it into the paper tube 13. As the paper tube becomes filled, it is moved further down upon the tube 7 and the 90 filling operation continued, until the quantity of tobacco required has been fully introduced and packed in the paper tube. The cigarette is then removed from the tube 7 and the end folded inward to seal the cigarette. 95 The tobacco bag 10 is then inverted, the tube 7 pushed fully inside and the draw strings tightened. In this condition the device, Fig. 1, is entirely shielded within the bag and the latter may be then placed in 100 the pocket.

The frame of wire may be made in various ways, as for example, such as shown in Figs. 4 and 5. In Fig. 4, the wire is bent upon itself in the middle to provide the plunger 110 6^a, and the parts 2 and 4 are then bent to provide a rectangular frame and their ends

bent into oppositely directed semi-circular parts 3^a to form the circular guide for the tube 7 and the ends soldered or welded at 5^a to complete the frame. The tube 7 would be 5 guided through the aperture formed by the parts 3^a, as indicated in dotted lines. In the modification shown in Figs. 5 and 6, the parts correspond to what is shown in Fig. 1, except that the wire part 2 is omitted and 10 the upper end of part 4 made continuous with the plunger 6 and with a horizontal return bend 15 (Fig. 5).

In Fig. 7, I have shown a further modification wherein the container is a metal box 15 10 having a hinged cover 11^a and the tube 7 guided through a hole 3^b at the end opposite to the cover. The plunger 6 may be of a wire secured to the container case 10^a at its end near the cover 11^a by being soldered or 20 welded thereto at 5^b. The narrow dimension of the container is shown in Fig. 7 but the other dimension may be considerably wider, to more nearly approximate the general shape of the bag, Fig. 3.

25 While the frame is preferably of wire and the tube 7 of metal, such as drawn aluminum, the latter may be made of celluloid, vulcanized fibre, cardboard or any other material found suitable.

30 The wire frame holds the bag distended so that the tobacco may freely fall into the tube 7 under manipulation and in case of longer cut tobacco, the plunger 6 will positively push the same through the tube and 35 pack it in the cigarette tube 13.

In all of these cases there is a plunger part (6, 6^a and 6^b) having one end free and the other end continued or extended, directly or indirectly, backward to the vicinity 40 of the free end of the plunger and provided thereat with a guide in which the tubular cigarette form 7 is guided.

It will now be apparent that I have devised a novel and useful construction which 45 embodies the features of advantage enumerated as desirable, and while I have in the present instance shown and described the preferred embodiment thereof which has been found in practice to give satisfactory 50 and reliable results, it is to be understood that I do not restrict myself to the details, as the same are susceptible of modification in various particulars without departing from the spirit or scope of the invention.

55 Having now described my invention, what I claim as new and desire to secure by Letters Patent, is:—

1. In a cigarette making device, a plunger having one end free, and a frame connected 60 to the other end of the plunger and extending in the direction of the length thereof to the vicinity of its free end and provided thereat with a guide immediately in front of the said free end of the plunger and 65 slightly separated therefrom, combined with

a reciprocable tubular cigarette form and filler arranged in alinement with the plunger so as to receive the same and guided by the guide on the frame.

2. The invention according to claim 1, 70 wherein the guide is in ring shaped form and the tubular form and filler extending through the ring shaped guide and having its end extended laterally to prevent disengagement with the guide. 75

3. The invention according to claim 1, further combined with an enclosing casing 80 for containing the tobacco and having the tubular cigarette form and filler extending from the inside to the outside of the casing 80 and reciprocable relatively thereto.

4. The invention according to claims 1 and 3, further characterized by the casing being in the form of a bag, provided with an open end having closure devices for 85 tightening the open end of the bag about the reciprocable tubular form and filler and for permitting the complete covering of the same when desired for transportation.

5. In a cigarette making device, the combination of a bag having a closure, a light metal frame of general rectangular shape fitting the bottom and sides of the bag to keep it distended and having a ring shaped 90 guide formed in one end part of the frame 95 and a plunger extending from the other end part of the frame and having its free end terminating in line with the opening in the ring shaped guide, and a tubular cigarette form and filler open at both ends and loosely 100 guided through the ring shaped guide and extending through the bag, whereby the cigarette paper may be wrapped about the tubular form and filler, and thereafter filled 105 with tobacco by reciprocating the bag and plunger relatively to the tubular form and filler.

6. The invention according to claim 5, further characterized by having the inner 110 end of the tubular form and filler flared so as to prevent its withdrawal from the ring shaped guide and to permit the tobacco plunger end to freely enter during making of a cigarette.

7. In a cigarette making device, the combination of a rectangular wire frame having the middle part of one of the sides of the frame formed into a ring shaped guide opening and the side diametrically opposite formed with a plunger having its free end 115 extended in alinement with the ring shaped guide and terminating at a short distance from said guide, and a tubular form and filler open at both ends and loosely guided through the ring shaped guide and reciprocable relatively to the plunger. 120

8. In a cigarette making device, the combination of a rectangular wire frame having the middle part of one of the sides of the frame formed into a ring shaped guide 125 130

opening and the side diametrically opposite formed with a plunger having its free end extended in alinement with the ring shaped 5 guide and terminating at a short distance from said guide, a tubular form and filler open at both ends and loosely guided through the ring shaped guide and reciprocatable relatively to the plunger, and a bag

enclosing the rectangular frame and the inner end of the tubular form and filler, 10 said bag provided with closure devices for closing the bag about the rectangular frame and inner end of the tubular form and filler.

In testimony of which invention, I hereunto set my hand.

RODNEY S. PULLEN.
